(57) **CLAIM**

The ornamental design for a mobile computer, as shown and described.

DESCRIPTION

FIG. 1 is a top front right perspective view showing a first embodiment of my new design;

FIG. 2 is a bottom rear left perspective view showing a first embodiment of my new design;

FIG. 3 is a front view of the first embodiment of my new design;

FIG. 4 is a rear view of the first embodiment of my new design;

FIG. 5 is a left side view of the first embodiment of my new design;

FIG. 6 is a right side view of the first embodiment of my new design;

FIG. 7 is a top view of the first embodiment of my new design;

FIG. 8 is a bottom view of the first embodiment of my new design;

FIG. 9 is a top front right perspective view showing a second embodiment of my new design;

FIG. 10 is a bottom rear left perspective view showing a second embodiment of my new design;
FIG. 11 is a front view of the second embodiment of my new design;
FIG. 12 is a rear view of the second embodiment of my new design;
FIG. 13 is a left side view of the second embodiment of my new design;
FIG. 14 is a right side view of the second embodiment of my new design;
FIG. 15 is a top view of the second embodiment of my new design;
FIG. 16 is a bottom view of the second embodiment of my new design;
FIG. 17 is a top front right perspective view showing a third embodiment of my new design;
FIG. 18 is a bottom rear left perspective view showing a third embodiment of my new design;
FIG. 19 is a front view of the third embodiment of my new design;
FIG. 20 is a rear view of the third embodiment of my new design;
FIG. 21 is a left side view of the third embodiment of my new design;

FIG. 22 is a right side view of the third embodiment of my new design;
FIG. 23 is a top view of the third embodiment of my new design;
FIG. 24 is a bottom view of the third embodiment of my new design;
FIG. 25 is a top front right perspective view showing a fourth embodiment of my new design;
FIG. 26 is a bottom rear left perspective view showing a fourth embodiment of my new design;
FIG. 27 is a front view of the fourth embodiment of my new design;
FIG. 28 is a rear view of the fourth embodiment of my new design;
FIG. 29 is a left side view of the fourth embodiment of my new design;
FIG. 30 is a right side view of the fourth embodiment of my new design;
FIG. 31 is a top view of the fourth embodiment of my new design; and,
FIG. 32 is a bottom view of the fourth embodiment of my new design.
